R. ELLIS,
Chain-Needles.

N° 15,006.

Patented June 3. 1856.

UNITED STATES PATENT OFFICE.

RUFUS ELLIS, OF BOSTON, MASSACHUSETTS.

NEEDLE FOR KNITTING-MACHINES.

Specification of Letters Patent No. 15,006, dated June 3, 1856.

To all whom it may concern:

Be it known that I, RUFUS ELLIS, of Boston, in the county of Suffolk and State of Massachusetts, have invented a new and useful Improvement in Needle-Chains of Rotary Knitting-Machines; and I do hereby declare that the same is fully described and represented in the following specification and the accompanying drawings, of 10 which—

Figure 1, exhibits a front elevation of a portion of one of my improved needle chains; Fig. 2, a front elevation of one needle link thereof; Fig. 3, a side view of a needle link; 15 Fig. 4, a transverse section of it; Fig. 5, a top view of it.

The endless needle belt on which my improvement is based is of a kind which will be found described in Letters Patent numbered 8163, and granted to William M. Chase, as assignee, July 17th 1837, the device covered by such patent having been invented by me. A belt of like character will also be found in the patent granted to 25 Erasmus French, on the 18th day of March A. D. 1842. During the operation of knitting with such endless needle belts, the performance of the process of "narrowing" requires the removal from the belt of one or 30 more of the needle links as occasion may require. And so with regard to the process of "widening" the work, such requires the endless chain to be increased in size by the addition of one or more links. In the common mode of making these needle chains, 35 their links have been so hinged together that in order to separate one of them from another it became necessary to draw the connecting rod longitudinally, out of the 40 joint of the hinge, the said rod being a separate piece of metal. Such an operation often requires much time and trouble to complete it. I have therefore sought to diminish the same, or in other words to so improve 45 the hinge in its construction as to enable its parts to be readily detached without the necessity of separating the rod from more than one of them, it being firmly attached to, so as to be a part of the other 50 or male portion of the hinge.

In the drawings, each link is represented at A, A, A, as provided in the usual way with a hooked needle, a, which may be arranged either in the plane of the chain or at

right angles thereto. The male part b, of 55 each link is provided with journals, c, d, which extend from it as seen in Figs. 2, and 3 or it may have a rod extended entirely through it, made fast in it and projecting from it so as to form journals, as shown at 60 c, and d. The female part of the hinge is composed of a recess e, and two socket tubes f, g, or their equivalents arranged on the link and with respect to the male part, b, as shown in Figs. 1, 2, and 3. The said 65 female socket is to be constructed in such manner as to enable a male part with its journals, or the latter to be moved downward and laterally in order to enable a person to detach the said male and female parts 70 from one another, when they make portions of the hinge. For this purpose, I make the recess e, in length equal to that of one of the journals, c, and the part b, from which, 75 it projects, and which is to enter the recess e, of a contiguous link. I also form the lower socket tube g, so much larger in diameter than the journal d, which is to work therein, as to enable the male part of the hinge or the link to be moved laterally out 80 of the recess e, far enough to enable the journal d, to be withdrawn from the tube g. In order to prevent the male and female parts of the hinge from accidentally becoming 85 disengaged, while in engagement, I apply to the socket tube, g, a spring stop i', and so that the same may serve as a shoulder or bearer to keep the journal, c, within its socket tube f, while the chain is in use. In order to detach the male and female 90 parts of the hinge, it will first be necessary, in case a spring stop is used as described, to move said spring stop laterally from underneath the lower end of the part b. When a chain has its links so constructed it 95 will be an easy matter, either to separate any one from the rest, or to supply such chain with a new link as occasion may require.

Having thus described my invention, what 100 I claim consists in—

Making the journal, c, d, or connecting rod of the hinge fast to the male or entering projection, b, thereof, in combination with so constructing the female socket of 105 the hinge as to enable the male part or its journals to be moved downward and laterally, in order to detach the same from the

female part and providing such female part with a spring stop or its equivalent, whereby when the male and female parts of the hinge of two links are connected together 5 they may be prevented from accidental disengagement as hereinbefore explained.

In testimony whereof I have hereunto set

my signature this first day of May A. D. 1856.

RUFUS ELLIS.
